UNITED STATES PATENT OFFICE.

WALTER V. HART, OF JACKSONVILLE, FLORIDA, ASSIGNOR TO SIMON F. WILLIAMS,
OF JACKSONVILLE, FLORIDA.

BOX-PRESS.

1,352,749.

Specification of Letters Patent. Patented Sept. 14, 1920.

Application filed August 1, 1919. Serial No. 314,670.

To all whom it may concern:

Be it known that I, WALTER V. HART, a citizen of the United States, residing at Jacksonville, in the county of Duval and 5 State of Florida, have invented a new and useful Box-Press, of which the following is a specification.

This invention relates to box clamping devices and more particularly to clamping 10 or pressing mechanism for holding the lids of fruit packing boxes or containers in position while being nailed or otherwise secured to the box.

An object of this invention is to provide 15 a foot operated mechanism of novel construction for clamping the lid upon citrus fruit boxes and the like, and novel means for locking the device in its clamped position.

Another object of this invention is to provide novel means for releasing the clamping device after the cover has been securely nailed to the fruit box or container.

A further object of this invention is to 25 provide a box pressing or clamping device of generally improved construction, whereby the device will be simple, durable and inexpensive in construction, as well as efficient in its use.

With the foregoing and other objects in view which will appear as the description proceeds, the invention resides in the combination hereinafter described and claimed, it being understood that changes in the precise 35 embodiment of the invention herein disclosed, can be made within the scope of what is claimed without departing from the spirit of the invention.

The invention has been illustrated in its 40 preferred embodiments in the accompanying drawings wherein:—

Figure 1 is a front view of the device, parts being broken away.

Fig. 2 is a plan view of the invention.

Fig. 3 is a vertical sectional view of the device, showing it in its clamping or pressing position.

Fig. 4 is a similar view showing the device in its released position.

Referring to the drawing there is shown a frame comprising vertically disposed supports or legs 5, a box supporting platform or table 6 and spaced uprights 7. This frame may be of any preferred construction 55 and it is to be understood that the frame

herein disclosed is only indicative of one form that may be advantageously employed in connection with the mechanism to be disclosed.

Bearing plates 8 are provided and have 60 elongated slots 9 formed therein for the reception of bolts or other securing devices 10 which adjustably secure the plates 8 to bars 11 that are slidably secured to the upright 7 by means of straps or bearings 12. 65

Toggle mechanism are provided and include relatively short links 13 and long links 14. The outer terminals of the long links 14 are pivotally secured to the plates 70 8, and the outer terminals of the short links 13 are pivotally secured to the uprights 7. 70

A composite lever structure is shown and is provided with spaced arms 15 that are united at their forward ends to provide a 75 foot treadle 16, and the rear ends of the arms 15 are journaled in bearings 17 carried by the upright 7. Short lever arms 18 are also journaled to the bearings 17 and these arms are rigidly secured to the arms 15 by means of braces or straps 19, thereby providing a 80 bell crank lever structure which operates as a unit. The terminals of the short lever arms 18, which are remote from the bearings 17, are connected with the inner or adjacent ends of the toggle links 13 and 14 through 85 the instrumentality of connecting links 20.

Retractile springs 21 have their upper terminals secured to the upper terminals of standards 7 by means of depending hooks 22 and the lower terminals of these springs are connected with the plate 8, by means of 90 hooks or other securing devices 23, which springs serve to normally hold the bars 11 in their elevated position. Gripping arms 24 extend horizontally from the upper terminals of the sliding bars 11 toward the 95 front of the machine.

A stop member or strip 25 is adjustably secured to the upper face of the table 6 and is adapted to limit the rearward movement 100 of a fruit box B, to thereby properly position this box upon the table 6 in order that its cover or closure may be engaged by the arms 24, as will be hereinafter disclosed.

Releasing levers 26 are pivotally secured 105 to the frame as shown at 27. The outer or front terminal of the levers 26 are provided with foot treadles 28, while the inner or rear terminals 29 of the levers 26 lie in the path of travel of the lever 15 to operably engage 110

the lever 15 during the operation of the device.

In operation the fruit box is positioned upon the table 6 in engagement with the 5 guide member 25 and then the treadle end of the lever 15 is moved downwardly by the foot of the operator, which causes the toggle mechanism to force the bars 11 and arms 24 downwardly into engagement with the cover 10 of the fruit box. Further downward movement of the lever 15 will cause the adjacent ends of the toggle links 13 and 14 to move past the dead center points and rest against the bar 11 or other stop means as indicated 15 at 30. Now the cover member C has been forced into proper position upon the fruit box B and where it may be readily nailed or otherwise secured to the box. The toggle mechanism may be readily released by simply pressing on the treadle 28 of one of 20 the levers 26 which causes the end 29 of this lever to engage the lever 15 and move the toggle mechanism from its locked position, which allows the retractile springs 21 to 25 raise the sliding bars 11 and arms 24, thereby releasing the box. The fruit box may now be removed and another placed upon the table and the above described operation may be repeated.

30 Having thus described my invention, what I claim is:

1. A device of the class described including a frame comprising a table and an upright, a composite bell crank lever journaled 35 to the said frame, a bar slidably secured to the said upright, a gripping arm carried by the said bar, a toggle mechanism operably connected with the frame and the sliding bar, a link operably connecting the toggle mechanism and the said bell crank lever in order to allow the said bell crank lever and 40 toggle mechanism to slide the arm 11 downwardly to a locked position, a retractile spring having one terminal secured to the 45 said sliding bar and the opposed terminal secured to the upright and adapted to slide the said bar upwardly, and means for engaging the bell crank lever and releasing it from the locked position.

50 2. A device of the class described including a frame comprising a table and an upright, a bar slidably secured to the said up-

right, a toggle mechanism operably connected to the lower terminal of the bar and to the said frame, a gripping arm carried by the sliding bar, and adapted to engage the cover member of a fruit box, a link having one terminal connected to the toggle mechanism, a composite bell crank lever journaled to the frame and operably connected with the link to thereby move the toggle mechanism past a dead center to a locking position, a lever pivotally secured to the said frame having one terminal in the path of travel of the bell crank lever and adapted to engage the said bell crank lever to release the bell crank lever from its locking position, a retractile spring having one terminal secured to the upright and the opposed terminal adjustably connected to the sliding bar, and 70 adapted to normally hold the said bar in its upright position.

3. A device of the class described including a frame comprising a table and an upright, said table adapted to support a container, a guide strip adjustably secured to the table and adapted to limit the movement of the container upon the said table, a bar slidably secured to the said upright, a gripping arm extending perpendicularly from the upper terminal of the said bar and adapted to engage the cover member of the container, an adjusting plate having elongated slots formed therein, means for adjustably securing the plate to the said bar, a toggle mechanism operably connected with the adjusting plate and the frame, a link operably connected with the toggle mechanism, a composite bell crank lever operably connected with the link to thereby move the toggle mechanism past the dead center to a locking position, a lever pivotally secured to said frame and adapted to operably engage the bell crank lever to release it from its locking position, and a retractile spring to 90 normally support the sliding bar in an elevated position.

In testimony that I claim the foregoing as my own, I have hereto affixed my signature in the presence of two witnesses.

WALTER V. HART.
